UNITED STATES PATENT OFFICE.

WILLIAM ERASTUS WILLIAMS, OF CHICAGO, ILLINOIS.

ROLLER SIDE BEARING FOR RAILWAY-CARS.

1,240,636.

Specification of Letters Patent. Patented Sept. 18, 1917.

Application filed August 27, 1914. Serial No. 858,792.

To all whom it may concern:

Be it known that I, WILLIAM ERASTUS WILLIAMS, a citizen of the United States, residing at Chicago, in the county of Cook, State of Illinois, have invented a new and useful Roller Side Bearing for Railway-Cars, of which the following is a specification.

My invention relates to a bearing which is interposed between the truck bolster and the body bolster of railway cars at the outer end thereof, and is sometimes called the outer bearing as a distinction between the center bearings or center plate between the bolsters of the car body and the car truck.

The object of my invention is to produce a cheap, simple, and efficient antifriction side bearing, and one which will readily return to its normal position for service at all times, and will at no time require a friction slip as the car turns curves.

Reference will be had to the accompanying drawings, in which Figure 1, is a top plan view of my bearing. Fig. 2 is a central sectional elevation on line 2—2 of Fig. 1. Fig. 3 is a vertical cross-sectional elevation on line 3—3 of Fig. 1. Fig. 4 is a perspective view of the rocker plate or steel face plate of the bearing.

The truck bolster and body bolster themselves, are not shown in the drawings, but the dotted lines, 1 in Figs. 2 and 3 indicate the truck bolster and the dotted lines 2 in the same figures indicate the body bolster. 3 indicates the main housing casting of the bearing which is a sort of open box fastened to the truck bolster by means of rivets, through holes 4. Inside of this box there are slots 5 which engage the ends of a pin 6 which passes through the anti-friction roller 7 of the bearing. The pin 6 fits loosely through the center hole of the roller 7, and also loosely in the slots 5.

The pin 6, is inserted in its position through a cored hole 8 in the side wall of the box 3, and after the pin is inserted, this hole is dammed off by means of the rivet 9 which passes down through some lugs 10 integral with the box casting. In the body of the box there are studs or projections 11 cast integral with the box. The curved steel plate 12 provided with the holes 13 as is shown by Fig. 4, is placed in the box in position over the projections 11, before the roller and pin are put in. Then after the

pin is inserted this plate 12 cannot be removed since some one of the projections 11 will engage some one of the holes 13, at all times as the roller cannot be lifted out of the housing or box on account of the pin 6 engaging the slots 5, hence this rocker plate must at all times remain in position for action within the box space of the casting 3.

When the car turns a curve of maximum curvature, the roller 7 will travel to the end of the box as indicated by the dotted lines 14 in Fig. 2, thus lifting the other end 15 of the plate 12 as shown by the dotted lines and when the plate is in this position the uplifted end of the plate acts as a lever and induces the return of the roller to central position at any time when the load is lifted from it by the rocking of the car body on the center bearing.

The adjustment of the center plates and side bearings of truck bolsters, are usually such that on a normal level straight track when the car is evenly loaded, the whole load will be put on the center plate, leaving a little clearance over each side bearing, but when the car rocks, as it does owing to inequalities of the track, curves and loading, then the load is applied and lifted off from the side bearings a great many times so that it often happens that after the anti-friction roller of the side bearing has been carried to one end of its travel, the car rocks, frees the roller, and the car may then turn another curve and come back to a straight track without engaging the roller of the side bearing, and were the roller to remain where it had been left at its outer position of travel, then on turning another curve in the same direction of travel, the side bearing roller would no longer be operated as a roller but there would be a friction slip on the roller, inducing wear of a flat spot, making useless the anti-friction device.

But the rocker plate of my side bearing, always returns the roller to its central position by means of the gravity action of the plate, causing the roller always to be ready to work as an anti-friction device.

Devices of this kind must be cheap in order for the railroad companies to use them at all, and simplicity is an all important item in the use of a bearing. The housings of side bearings of this nature are usually made out of malleable iron or cast steel which materials are not very hard, and the oscillation of the load upon the roller or

rather what may be termed the pounding of the car on the side bearing roller, induces indentations into the soft metal track of the roller, when the latter is made of cast steel or malleable iron, so that it is desirable to face the track upon which the roller rides with a steel plate harder than the materials of the casting.

I make the rocker plate 12 of steel, and cause it not only to perform the function of bringing the roller to its normal position, but also to act as the facing plate for the bearing and thus I save expense in the cost of the bearing over other devices which seek to accomplish the same purposes.

The cost of labor in making my bearing is the minimum of any other bearing having anything like the same or equivalent merits, since there is almost no labor in assembling the parts. The parts are simply placed together and the rivet 9 fastened, and the bearing is finished.

In place of the rivet 9, I may use any other suitable means, such as a cotter pin, bolt, key or other locking device with which to dam off the hole through which the pin is inserted.

Should the bearing need repairs at any time, the rivet 9 is removed and the pin driven out by any suitable tool, inserted through the hole 16, thereby forcing the pin 6 out of the housing and thus freeing the roller and the plate. The rollers used in bearings of this kind are usually made very hard so as to stand without deformation, the pounding that they receive in service.

In the side walls of the box of the casting 3, there are apertures 17 and 18 at the sides of the housing, and 19 and 20 at the ends. These apertures permit the free escape of any dirt or foreign matter that might happen to come within the box in the housing.

It is desirable that a rocker plate be made as thin as can be made, and yet sufficiently stiff to prevent its being bent or distorted under the load of the roller, for the reason that the thinner the plate, the lower its center of gravity and the more it acts in bringing the roller to its own center. And when the thickness of this plate is a large percentage of the radius of the roller, it seems to have much less effect to return the roller to its normal position. This may be due in part to the extra inertia and resistance in moving itself, and further to the

fact that the center of gravity of the thicker plate is higher up, and as the plate rocks, it passes through less distance of travel, giving less moment in proportion to its weight to return the roller to its normal position.

It is desirable to have the engaging projections which interlock the plate 12, and the casting 3 upon the casting and have the holes in the plate instead of having projections on the plate and holes in the casting. The plate is more sensitive in the arrangement as I have shown than the other way. It is cheaper also to make the projections of the interlocking means between the plate 12 and housing 3 on the casting and make the hole in the plate.

I prefer to call the bottom of the housing whereon rocks the plate 12, a track face as will be noticed in the claims.

What I claim is:

1. In a device of the class described, the combination with a housing of a bottom track surface with upwardly extending projections, a curved rocker plate adapted to rest upon said surface and provided with recesses to receive said projections, respectively, and a weight-receiving roller held against upward displacement resting upon said rocker plate, substantially as set forth.

2. The combination with an elongated box-like housing having at its bottom a track surface and guideways in its lateral walls, of a curved rocker plate resting upon said surface and provided with a series of recesses, and a weight-receiving roller resting upon the concave surface of said plate, traveling along said guideways and held therein against upward displacement; said bottom being provided with upwardly extending projections of a length not exceeding the thickness of the plate and adapted to fit loosely in said recesses, respectively.

3. The combination with an elongated box-like housing having at its bottom a track surface, of a curved rocker plate resting on that surface and a roller resting upon the rocker plate and held against upward displacement, the end walls of the housing being cut away at their lower sides below and beyond the upwardly curved margins of the rocker plate.

WILLIAM ERASTUS WILLIAMS.
